UNITED STATES PATENT OFFICE.

EDWARD L. MORAN, OF DAYTON, OHIO, ASSIGNOR TO CHARLES A. WILLEY, OF NEW YORK, N. Y.

WHEEL-PAINTING MACHINE.

No. 796,442.

Specification of Letters Patent.

Patented Aug. 8, 1905.

Application filed January 23, 1905. Serial No. 242,341.

To all whom it may concern:

Be it known that I, EDWARD L. MORAN, a citizen of the United States, residing in Dayton, in the county of Montgomery and State of Ohio, have invented certain new and useful Improvements in Wheel-Painting Machines, of which the following is a full, clear, and exact description, reference being had to the accompanying drawings, forming part of this specification.

My invention relates to machines for the painting of wheels, in which the wheel is mounted on an endwise-movable shaft within a tank partially filled with the paint to be applied and in which mechanism is provided for reciprocating the shaft to coat the wheel and then to rotate the wheel to cause the paint to flow over every portion thereof. Heretofore in such wheel-painting machines mechanism has been provided for rotating the shaft in one direction only and no provision has been made for properly controlling and varying the speed of the rotating shaft.

My invention therefore consists of that certain novel construction and arrangement of parts, to be hereinafter particularly pointed out and claimed, whereby the wheel-carrying shaft may be rotated in either direction or its rotation reversed, as desired, and in which the speed of the shaft may be varied at will, so that when desired the wheel may be rotated very slowly when immersed in the coating material and the material properly agitated and mixed.

In the drawings, Figure 1 is a plan view of my improved machine with the wheel in place. Fig. 2 is a front elevation of same, partly in vertical section. Fig. 3 is a detail of the speed-controlling and shifting mechanism.

1 is a cylindrical tank of suitable diameter and depth to conveniently hold the wheel 2 to be painted either in or out of the paint. This tank is supported at a convenient height from the floor by standards or legs 3. The central portion of the bottom of the tank is provided with a semispherical plate 4, and extending vertically through the center of this plate is an endwise-movable shaft 5. 6 is a suitable stuffing-box for this shaft. Extending upward from the shaft 5 a sufficient distance to conveniently receive the hub of the wheel is a spindle 7, and 8 is a fork mounted on the end of the shaft 5 within the tank and

held in proper position by the set-screw 9. The outer ends of the fork are provided with knobs 10, and the wheel 2 is held in position on the shaft to rotate and move with it, as hereinafter described, by setting the hub on the spindle 7 and allowing the ends of the fork to embrace the spokes on opposite sides.

The shaft 5 is driven in either direction by the friction-gear, consisting of the clutch-sleeve 28, feathered to slide on the shaft 5 in the keyway 11 and carrying the beveled disks 12 and 13, fast thereon, which mesh with the driving-pinion 21, preferably formed of compressed paper or other suitable material, to frictionally engage and rotate either of the disks 12 or 13, and thus to rotate the shaft in either direction as either of the disks is brought into contact with the driving-pinion 21 by shifting the hand-lever 17, which is pivoted in a suitable support 16 on the frame and has bolted to its outer end the shifter-fork 15, carrying the beveled rollers 14, which engage in the groove between the disks 12 and 13 on the clutch-sleeve 28. The driving-pinion 21 is mounted on the end of the driving-shaft 18, provided with the usual tight and loose pulleys 19 and 20 for driving same from suitable power.

The lower end of the shaft 5 is provided with a collar 22, adjustable thereon by a set-screw to vary the throw of the shaft, and this collar is engaged by the shoe 23, pivoted to the end of the lever 24. Lugs 25 are provided on the shoe to engage the upper surface of the collar 22, so that by the hand-lever 24 the shaft 5 may be moved in both directions. The lever 24 is pivoted in the support 26, depending from the cross-piece of the frame. The two operating-levers 17 and 24 are guided by the sector-frame 27, and notches are provided in this frame to lock the levers in any desired position.

In using the machine the tank 1 is first partly filled with the desired paint or coating material. The shaft 5 is then raised by depressing the hand-lever 24 and locking it down. The wheel to be painted is then placed on the spindle 7 and held in position by the fork 8. The lever 24 is then returned to its upright position, which draws down the shaft 5 and immerses the wheel in the paint. If desired, the lever 17 can then be operated slightly to obtain a slight friction clutch between either of

the beveled disks 12 or 13 and the cone-pinion, so as to give a very slow movement to the wheel to use it as an agitator or mixer of the paint. In either event as soon as the wheel is coated the lever 24 is depressed, which raises the shaft 5, and the wheel is raised out of the paint. The lever 24 is then locked down and the lever 17 operated to bring the disk 12 in engagement with the pinion to rotate the wheel in one direction very rapidly, and this engagement is then released and the lower disk 13 is brought into engagement with the pinion and the wheel rotated rapidly in the opposite direction. The other disk 12 is then used to serve as a brake to stop the rotation of the shaft, and the wheel is removed and another one substituted for further operation.

I have found that by rotating the wheel rapidly first in one direction and then in the other the flow of the coating material is much more even than it is when the wheel is only rotated in one direction. The friction-clutch gearing also forms a very important part of my invention. I am able to rotate the wheel slowly while in the paint and also to start and stop the rapid rotation when the wheel has been raised from the paint slowly and smoothly without any jerking or wear and tear on the mechanism.

In order that it may not be necessary to clean out the tank when a paint of one color has been used to make use of another color, I provide one or more tanks similar to tank 1, with an opening in the center, but without the semispherical central portion 4. By loosening the bolts by which the tank 1 is secured to the central portion 4 these additional tanks, which are of somewhat less diameter than the tank 1, can be in a moment secured in place. The additional tanks are of slightly-smaller diameter, so that they can be easily located within tank 1, and the central opening in these additional tanks is protected by a flanged collar, so as to make a tight joint with the rim of the semispherical base 4 when bolted in place. In order to draw off the paint from the tanks, the plate 4 is provided with an

eduction-pipe with suitable stop-cock therein. (Not shown.)

Having thus described my invention, what I claim as new, and desire to secure by Letters Patent, is—

1. In a wheel-painting machine, a tank for the reception of the paint-bath, a rotatable and shiftable shaft projecting into said tank, and upon which shaft the wheel to be painted is mounted, means for shifting said shaft to immerse and withdraw the wheel from the bath, with mechanism for reversing the rotation of said shaft, substantially as described.

2. In a wheel-painting machine, a tank for the reception of the paint-bath, a rotatable and shiftable shaft projecting into said tank, and upon which shaft the wheel to be painted is mounted, means for shifting said shaft, to immerse and withdraw the wheel from the bath, with means for frictionally driving said wheel-carrying shaft to operate same at varying speeds and without jar in starting and stopping, substantially as described.

3. In a wheel-painting machine, a tank for the reception of the paint-bath, a rotatable and shiftable shaft projecting into said tank, and upon which shaft the wheel to be painted is mounted, means for shifting said shaft, to immerse and withdraw the wheel from the bath, a power-driven shaft, with means for frictionally connecting same to the wheel-carrying shaft whereby varying speeds may be obtained, and said shaft started and stopped without jarring, substantially as described.

4. In a wheel-painting machine, a tank for the reception of the paint-bath, a rotatable and shiftable shaft projecting into said tank, and upon which shaft the wheel to be painted is mounted, means for shifting said shaft to immerse and withdraw the wheel from the bath, with friction gear and clutch mechanism for rotating said shaft in either direction, substantially as described.

EDWARD L. MORAN.
